UNITED STATES PATENT OFFICE.

HUGH T. REED, OF CHICAGO, ILLINOIS.

CALENDAR.

1,399,880.

Specification of Letters Patent. Patented Dec. 13, 1921.

Application filed April 18, 1921. Serial No. 462,209.

To all whom it may concern:

Be it known that I, HUGH T. REED, a citizen of the United States, residing at Chicago, in the county of Cook and State 5 of Illinois, have invented certain new and useful Improvements in Calendars, of which the following is a full, clear, and exact specification.

This invention relates to calendars and 10 has for its object to provide improved and simplified means for supporting a plurality of packs of calendar cards in plain view and in such a way that the cards of either pack may be adjusted or turned from the 15 front to the back of said pack without interfering with the cards of the other pack.

Another object is to provide a simple 20 device for supporting one of the packs of cards at an inclination to the plane of the cards of the other pack, so that the outside cards of both packs are in more convenient view of the user. A further object is to provide a compact index to the calendar cards 25 so that the device may be used as a perpetual calendar. Another object is to provide a detachable casing for either of the packs of cards, the outside cards being visible at the front and back of said casing.

Other objects will appear as the description 30 proceeds.

The invention will be first hereinafter described in connection with the accompanying drawings, which constitute part of this specification, and then more specifically defined in the claims at the end of the description.

In the accompanying drawings, wherein 40 similar reference characters are used to designate corresponding parts throughout the several views:

Figure 1 is a front elevation of a perpetual calendar made substantially in accordance with the present invention, the lower pack of cards being inclosed in a 45 movable casing and supported in forwardly inclined position.

Fig. 2 is a rear elevation of the same, the lower pack of cards being supported in rearwardly inclined position.

Fig. 3 is an end elevation of the same, 50 part of the end support being broken away to disclose the relative positions of the two packs of cards, and the casing for the lower pack of cards being shown in section.

Fig. 4 is a detailed perspective view of 55 one of the century indexes on the reverse face of one of the monthly calendar cards.

Fig. 5 is a detailed perspective view of the reverse face of another one of said monthly cards bearing information as to the 60 use of the calendar, and

Fig. 6 is a detailed perspective view of the casing for the lower pack of cards, the interfitting members of said casing being shown separated for the purpose of illustration.

As illustrated in Figs. 1 and 2, the calendar cards are supported on a stand which is preferably made of sheet metal having a broad base 1 and upwardly extending and 70 tapering end portions or supports 2. A cross bar 3 extends horizontally between the supports 2 to the upper ends of which it is preferably fastened permanently.

There are two packs of cards, one pack 4 75 containing twelve small cards, and the other pack 5 consisting of twenty-eight larger cards. On the obverse faces of the small cards 4 are printed the twelve different names of the calendar months, one name on 80 each card, with the number of days in that month under the name, as shown in Fig. 1. On the reverse faces of these cards 4 may be printed "Hossier Perpetual Calendar," as indicated in Fig. 2.

On the obverse faces of the larger cards 5 are printed the twenty-eight different month calendars, one calendar on each card with a head-line identifying each calendar, as for instance, "31 Day Month Beginning 90 Wednesday," as illustrated in Fig. 1. There are four sets of month calendars, one for 31 days, see Fig. 1, one for 30 days, one for 29 days, and one for 28 days, and each card of each set begins on a different day of a week 95 which makes up the twenty-eight different month calendars. On the reverse faces of fourteen of the larger cards 5 are printed the fourteen different year calendars, one calendar on each card with a head-line identifying each calendar, as for instance, "365 Day Calendar Beginning Tuesday," as shown in Fig. 2. There are two sets of year

calendars, one for 365 days, and one for 366 days, and each set begins on a different 100 day of the week, which makes up the fourteen different year calendars. On the reverse face of another one of the cards 5 is printed "Index To The 18th Century," and on another card "Index To The 19th Century," and on still another card "Index To The 20th Century," see Fig. 4. On the reverse faces of as many other cards 5 as may be needed for the purpose, see Fig. 5, infor- 110

mation may be printed as to how the index may be extended to include other centuries, how to find the calendar for any year in the century that is indexed, how to find the day 5 of the week on which one was born, or on which any other event occurred, etc.

The cards 4 are supported from the cross bar 3 by rings or loops 6 which pass loosely through perforations 7 in said cards. These 10 cards 4 are considerably shorter than the cross bar 3, leaving room between their ends and the supports 2 for elongated loops 8 which are also hung from said cross bar and serve to support the pack of larger cards 5 15 below the pack of cards 4 and above the base 1.

It will be noted that the loops 8 swing clear of the ends of the monthly designation cards 4, so that the cards of either pack may 20 be adjusted or moved along its supporting loops from the front to the back, or vice versa, without interfering with the cards of the other pack. The cards 5 have perforations 9 through which the supporting loops 25 8 are loosely threaded in the same manner as the cards 4 are mounted on the loops 5.

Notches 10 are formed in the end supports 2 of the frame, entering from the edges of one front thereof and extending inwardly 30 a short distance, preferably at a slight incline to the horizontal, and similar notches 11 are formed in the edges of the other front of said supports, as best shown in Fig. 3. Into these notches a cross bar 12 is removably fitted for supporting the pack of cards 5 in inclined position so as to bring the front card into more convenient view of the user along with the front card of the pack 4, see 35 Figs. 1, 2 and 3. The ends of the removable cross bar 12 may be bent angularly, as at 40 13, or otherwise offset to retain said bar in engagement with the notches 10 and 11 against axial displacement. It will be understood that the bar 12 is placed in the 45 notches 10 in the edges of one front of the supports 2, as shown in Figs. 1 and 3, when a month calendar on the obverse face of the front card 5 of the larger pack is to be displayed, and that said bar 12 is engaged with 50 the notches 11 in the edges of the other front of said supports 2 when a year calendar card on the reverse face of a card of said pack is to be displayed, as indicated in Fig. 2.

Either of the packs of cards may be 55 closed in a removable casing, the cards 5 of the larger pack being shown equipped with such a casing in Figs. 1, 2 and 3. Said casing may be constructed in any suitable manner, as of two interengaging tray-like sections 14 and 15, Fig. 6, each having marginal flanges 16 and 17, respectively, to frictionally engage one within the other, as shown in Fig. 3. The sections of the casing also have openings 18 and 19, respectively,

through which the adjacent cards 5 may be 65 seen. Sheets 20 and 21, respectively, Fig. 3, of transparent material may be fitted over said openings within the casing for protecting the cards. The upper marginal portions of the sections of the casing are notched 70 at 22 to fit around the loops 8, so that said casing may be easily removed from the pack of cards 5 whenever it is desired to shift said cards on said loops. 75

I claim:

1. In a calendar, the combination with a stand having end supports, of a cross bar extending between the upper end portions of said supports, a pack of calendar cards hung from said cross bar, another cross bar for supporting the pack in inclined position for the purpose specified, there being transversely extending notches in the edges of said supports for detachably holding said last mentioned cross bar in place. 80 85

2. In a calendar, the combination with a stand having end supports, of a cross bar extending between the upper end portions of said supports, a pack of calendar cards hung from said cross bar, another cross bar for supporting the pack in inclined position for the purpose specified, there being notches in said supports for detachably holding said last mentioned cross bar in place, said notches being downwardly and inwardly inclined for retaining said detachable cross bar therein. 90 95

3. In a calendar, the combination with a stand having end supports, of a cross bar extending between the upper end portions of said supports, a pack of calendar cards hung from said cross bar, another cross bar for supporting the pack in inclined position for the purpose specified, there being notches in said supports for detachably holding said last mentioned cross bar in place, said detachable cross bar having offset ends for retaining it in the notches against axial displacement. 100 105

4. In a calendar, the combination with a stand having end supports, of a cross bar extending between the upper end portions of said supports, a pack of calendar cards hung from said cross bar, another cross bar supporting the pack in inclined position for the purpose specified, there being notches in the edges of both fronts of said supports for detachably holding said last mentioned cross bar in place, the notches in the edges of one front of the supports serving to hold said bar so as to support the pack of cards in a forwardly inclined position when that front is presented, and the notches in the edges of the other front of the supports serving to hold the bar so as to support the pack in a forwardly inclined position when said other front is presented. 110 115 120 125

5. In a calendar, the combination with a

stand having end supports, of a cross bar extending between said supports, a pack of cards, means for loosely supporting said pack of cards from said cross bar, and a detachable casing to inclose said pack of cards, there being notches in the marginal portion of said casing for the passage of said supporting means.

6. In a calendar, the combination with a stand having end supports, of a cross bar extending between the upper end portions of said supports, a pack of cards having all of the month calendars on the obverse sides thereof, a different calendar on each card, the reverse sides of fourteen of said cards having all of the year calendars thereon, a different one on each card, and the reverse sides of the other fourteen cards having indexes to several centuries and suitable in-

formation, said cards being hung from said cross bar, another cross bar supporting the pack in inclined position for the purpose specified, there being notches in the edges of both fronts of said supports for detachably holding said last mentioned cross bar in place, the notches in the edges of one front of the supports serving to hold said bar so as to support the pack of cards in a forwardly inclined position when showing a month calendar, and the notches in the edges of the other front of the supports serving to hold the bar so as to support the pack of cards in a forwardly inclined position when showing a year calendar.

In testimony whereof I have signed my name to this specification.

HUGH T. REED.
